UNITED STATES PATENT OFFICE.

LOUIS C. STUKENBORG, OF CHICAGO, ILLINOIS, ASSIGNOR TO FREDERICK W. STUKENBORG, OF CHICAGO, ILLINOIS.

COTTON-PICKER.

1,279,933.

Specification of Letters Patent. Patented Sept. 24, 1918.

Application filed January 10, 1918. Serial No. 211,176.

To all whom it may concern:

Be it known that I, LOUIS C. STUKENBORG, a citizen of the United States, and a resident of Chicago, in the county of Cook and State 5 of Illinois, have invented certain new and useful Improvements in Cotton-Pickers; and I do hereby declare that the following is a full, clear, and exact description thereof, reference being had to the accompanying 10 drawings, and to the characters of reference marked thereon, which form a part of this specification.

This invention relates to improvements in cotton picking machines, and refers more 15 particularly to that general type of machine illustrated in my United States Letters Patent No. 1,264,575, dated April 30, 1918.

The present invention relates to improvements in the take-off device by which the 20 cotton is removed from the picking brushes; to improvements in the mountings for the rotative picker brushes and the take-off device, designed to prevent the cotton fiber from wrapping about the rotating parts in a 25 manner tending to clog the machine; to novel means for counterbalancing the weight of the picker head and transmission tube, and means for supporting the flexible or jointed driving shaft in such a way as to 30 avoid "whipping" of the shaft, and relates further to other improvements and details of construction.

The invention consists in the combination and arrangement of the parts shown in the 35 drawings and described in the specification, and is pointed out in the appended claims.

Figure 1 is a side elevation of a cotton picking machine embodying my invention.

Fig. 2 is a fragmentary detail of the support for the counterbalancing device.

Fig. 3 is an enlarged plan view of the picker head.

Fig. 4 is a section on the line 4—4 of Fig. 3.

Figs. 5 and 6 are sections on the lines 5—5 and 6—6, respectively, of Fig. 4.

The frame 10 of the machine, the receiving basket 11, the motor 12 and the suction fan 13 follow closely the construction and arrangement shown in my aforesaid patent 50 and need not be further referred to. 14 designates a conveying tube for the cotton, to

the outer end of which is connected the picker head 15; the rear end of said tube communicating with the suction fan 13.

The picker mechanism of the head is 55 driven from a counter shaft 17 that is connected to and driven by the engine 12, through the medium of a jointed or flexible transmission shaft 20. Said transmission shaft consists of a number of sections of 60 straight or solid shaft that are connected by hinged joints 21, and are provided in a known way at their hinged ends with mating gears so constructed as to be maintained in mesh in all positions of adjustment of the 65 shaft sections relatively to each other. The terminal section 32 of said shaft (Fig. 4) is mounted in a suitable bearing in the head and is geared to the picker mechanism in the manner hereinafter described. 70

The weight of the head and conveying tube and also the transmission shaft, as herein shown, is counterbalanced by a counter-weight 23, which is supported in the bight of a cable 24, one end of which is attached 75 at 25 to the overhanging arm 26 of a standard 27. Said cable is trained about pulleys 28 mounted on said arm, and is attached at its other end, by means of a ring 29 and a clip 30, to the section of the transmission 80 shaft nearest adjacent to the countershaft 17. If desired, a cushioning spring 33 may be inserted into the cable 24 near its point of attachment to the transmission shaft. 75

The conveying tube 14 may be suspended, 85 at a point between its ends, from one section of the transmission shaft, as by means of a clip 34, which encircles said tube, and is provided with jaws that embrace the transmission shaft section, and said clip is clamped 90 to the tube and shaft by means of a clamping bolt 35 extending through apertures in said jaws.

The arrangement described provides means whereby the tube, the transmission shaft and 95 head are counterbalanced by the weight 23. The effect of this arrangement is to relieve the operator of the weight of the parts so that the head may be directed to the work without the necessity of carrying or lifting 100 the weight of the head, the shaft, and tube. This effect to counterbalance the weight of

the tube, shaft, and head will be attained whether or not the tube be connected to the shaft, as by the clip 34. The connection of the tube to the shaft is advantageous, however, because the tube is prevented from objectionable sagging when the head is operating adjacent to the frame.

The connection of the jointed transmission shaft to the counterweight avoids side 10 whipping of the shaft. A transmission shaft which is not supported between its ends, as at the section adjacent to the countershaft 17, has a tendency, when power is transmitted therethrough, to be shifted sidewise 15 with considerable force, or what is termed "whipping" to one side; and the weight of the shaft is sufficient to render this side movement of the shaft dangerous to the operator. Moreover the supporting of the 20 shaft 20 through the movable counterweight and its cable 24 enables the shaft to be extended or retracted as desired in use.

With respect to the counterbalancing of the parts and relieving the operator of the 25 work of carrying the weight of the head, shaft, and tube, the parts are so counterbalanced that, while the head will remain in any extended position in which it is placed, a slight force is required to depress it so that 30 the operator, instead of supporting the weight of the head, will, in effect, support a portion of his own weight on the head in depressing it when directing it to the work.

The standard 27 may be supported in any 35 suitable manner on the machine frame. As shown in Fig. 2, a step bearing 38 is attached to the frame at the bottom thereof and at one side, and said standard extends through an apertured supporting ear or 40 lug 39 fixed to the side of the frame near the top thereof. It will, of course, be understood that the particular manner of mounting the counterbalancing device may be varied, and if a hollow standard be employed, the counterweight 23 may be located 45 within the hollow standard.

The picker head mechanism shown in Figs. 3 to 6, inclusive, embraces in its construction two rotative brushes comprising 50 cores 40, 40 and angularly spaced rows of bristle tufts 41. Said brushes are fixed to upper and lower shafts 42 that are mounted in suitable bearings in the side walls 43, 44 of the head casing. They rotate in directions to cause them to move toward each other at the receiving side of the picker mechanism, as indicated by the arrows in Fig. 4.

The picker head casing is made principally of two lateral hollow members designated by 45, 46 in Fig. 3, which are connected together by screws 45' that extend through mating lugs 46' on the margins of said casing members. The two members of 65 the casing are fashioned to produce an en-

larged mouth portion 47, a rearwardly extending neck portion 48, to which latter the conveying tube is connected, and a throat portion 50. Said throat portion is somewhat restricted in vertical dimension, but is 70 widened in lateral dimension to give ample clearance for the passage of the cotton there-through. The vertical dimension of the throat is limited by upper and lower bearing blocks 52, which are attached to the upper 75 and lower walls of the throat portion of the casing by screws 53.

The shafts 42 of the rotary brushes are mounted in bearings carried by the side walls 43, 44, best shown in Fig. 5. Preferably anti-friction bearing rollers are interposed between the shafts and said side walls. As herein shown, the shafts carry at their outer ends hardened bearing rings 55, and the walls are provided with bearing 80 cups 56, between which and said rings are interposed spherical bearing elements 57. The said bearing cups 56 are fitted within annular sockets formed in inwardly extending flanges or hollow lugs 58, 59 carried by or made integral with the casing members 43 and 44, respectively.

As a further and separate improvement, the brushes are provided at their ends with endwise extending cylindric flanges or shells 95 60 which overlap and surround said hollow lugs 58 and 59, and extend at their ends closely adjacent to the side walls 43, 44 of the casing. The overlapping or telescopic arrangement of the hollow lugs of the casing 100 walls and the shells of the brush cores prevents access of cotton to the bearings, and avoids twisting of the cotton fiber about the bearings in a manner tending to clog the picker mechanism. This construction is also 105 advantageous, in that it affords smooth, unbroken and non-projecting walls in the passageway backwardly, through which the cotton is conveyed through the head, and further avoids matting of the cotton and the 110 breaking of the fibers thereof. The wall 43 is provided, adjacent to the bearings for the brush shafts 42, with enlarged openings through which the adjacent anti-friction bearings are inserted to place, and said openings are closed by screw threaded plugs 61.

Arranged in rear of the brushes and moving in contact with the bristles thereof is a rotary take-off device designated, as a whole 115 by 64, the function of which is to remove or 120 strip the cotton from the brushes. Said take-off device is generally like the take-off device illustrated in my aforesaid patent, in that it embraces a series of disappearing stripper pins which are projected outwardly 125 against the brush bristles on the side thereof adjacent to the brushes and which recede into a rotating inclosing member as they move away from the brushes, so as to strip 130 therefrom the cotton removed from the

brushes. The details of construction of the take-off device, herein illustrated, varies somewhat from the construction of the aforesaid patent, and are made as follows:

- 5 66 (Figs. 4 and 6) designates a shaft which is disposed at a right angle to the axes of rotation of the brushes. It is mounted in suitable bearings carried by the upper and lower walls of the picker head 10 casing. Said shaft extends through and has bearing in openings in the blocks 52, before referred to, which openings are disposed eccentrically with respect to the axes of said blocks. Mounted on said shaft between the blocks 52 is a sleeve 68. Said sleeve is provided near its ends with annular grooves 68^a, in which are seated the inner ends of stripping pins 69. Said pins extend radially from the sleeve and are 15 loosely connected thereto at said grooves by pivot pins 70 arranged longitudinally of the sleeve and intersecting said grooves. Said stripping pins 69 extend outwardly through apertures 71 in a shell 72 that surrounds the 20 sleeve and is disposed with its axis eccentric to the axis of rotation of said sleeve. As herein shown, said shell is provided at its ends with internal annular bearing faces 74 which engage peripheral bearing faces 75 25 at the ends of said blocks 52, whereby said shell rotates about an axis coincident with the axes of said blocks 52. A driving connection between said sleeve 68 and the shell 72 is herein shown as afforded by means of 30 a pin 76 which is rigidly fixed at its inner end to the sleeve and shaft and extends outwardly for engagement with an aperture in the shell. The apertures 71 in the shell through which the loosely attached stripping pins extend are enlarged or flared inwardly at the inner side of said sleeve so as to afford the required freedom of movement of the stripping pins therein in the 35 parts of the rotation of said device between the two extreme points where the pins project farthest through the shell and that where the pins are withdrawn farthest inwardly from the outer periphery of said shell.
- 40 The construction described, embracing the overlapping portions of the blocks 52 and the shell 72, is advantageous, in addition to the bearing thus afforded, in that the rotating parts of the take-off or stripper device are protected from the entrance of the cotton fiber thereto, so as to thereby avoid the cotton winding on the rotating parts of the bearing in a manner tending to clog the machine or cause it to bind. This construction, in connection with the similar protection of the bearings for the brushes, affords continuous, smooth walled passages for the cotton rearwardly from the brushes through the head, resulting in minimum 45 power to drive the machine, and also in a

minimum compression or compacting of the cotton passing therethrough. Because of the latter condition the cotton reaches the basket or receptacle 11 in a fluffy condition and in a good condition for ginning. For 70 the same reason the loose or fluffy cotton permits air, by which it is conveyed to the basket, to pass freely therethrough on its way to the storage basket so that damp cotton will be thereby virtually dried and also 75 dirt will be freed from the cotton fiber.

The shaft of the take-off device is provided at its upper end exterior to the casing with a beveled pinion 78, which meshes with a beveled pinion 79 on a horizontal 80 counter shaft 80 that is rotatively mounted in bearings in extension walls 81, 81 of the picker head casing. Said counter shaft is provided with a second beveled pinion 83, which meshes with a pinion 84 that is carried by the forward section 32 of the transmission shaft 20. Said shaft section 32 is rotatively mounted in a bearing 86, shown as formed integral with the upper wall of the member 46 of the picker head casing. 90 The said bearing embraces a removable cap piece 88, and the meshing gears 78, 79, 83 and 84 and the counter-shaft 80 are covered by a removable cover plate 90 attached by screws 91 to the casing. The removal of 95 said bearing cap 88 and cover plate 90 affords access to the nest of gears and to the associated shafts so that said parts may be readily inspected and repaired.

It will be observed that the section 32 100 of the transmission shaft is offset in respect of the center of the head. This construction is preferable, as compared to the construction shown in my aforesaid patent in that,—first, it is more practical to mesh a 105 pair of transmitting gears than a nest of three gears, and, second, because the location of said transmission shaft section 32 at one side of the longitudinal axis of the head largely, if not wholly, neutralizes the tendency of the head to twist in the hand, due to the driving force of the transmission shaft. Thus the head may be directed to its work with more comfort to the operator.

The brushes and take-off device are driven 115 in the direction indicated by the arrows in Fig. 4. Said brushes are rotated from the counter shaft 80, as will be evident from an inspection of Figs. 3, 4 and 5. As shown in said figures, 92 designates a toothed gear 120 which is fixed to one end of said counter-shaft, at the left hand side of the head, as herein shown. 93, 93 designate gear wheels at the same side of the head which are fixed to the shafts 42 of the brushes. Said gear 125 wheels 93 mesh with each other, and one of the latter gear wheels meshes with the counter-shaft gear wheel 92. The nest of gear wheels 92 and 93 are inclosed by a removable hollow cover plate 94 attached, as 130

by means of screws 95, to the side wall of the enlarged or mouth portion of the casing.

Guard fingers 97 are arranged partially 5 across the mouth of the head. They are herein shown as fixed to bars 98 that are removably set in and attached to the upper and lower walls of the picker head at the mouth, as by means of screws 99. Said 10 guard fingers extend toward but terminate short of each other. They are made of suitable spring metal, whereby they are springable toward the brushes when the cotton is directed into the head by the coaction of said 15 brushes. When the pressure of the inwardly moving cotton is removed the guard fingers spring to their normal positions and have the effect of throwing outwardly or rejecting hulls, pods or leaves intercepted by said 20 fingers.

The head is provided adjacent to the throat 50 with a receiving opening 100 through which air, set in motion by the exhaust fan 13, is driven into the head. The 25 air so set in motion backwardly through the head and tube 14 carries the cotton backwardly to the basket 11, and the opening 100 is so positioned that the movement of the air is confined principally to the region 30 of the head in the rear of the take-off device. Said opening is located on the side of the head near and closely adjacent to the side of the rotating take-off device which moves away from the brushes. As the take-off device moves away from the brushes the stripping pins retire or disappear into the shell 35 72, and it is at this part of the take-off device, and in a position where the pins are in most favorable position for the release of 40 cotton therefrom, that the incoming air strikes the cotton. Therefore, it becomes practical to direct the air, not only to carry the cotton back after it has been released from the take-off device, but to assist the 45 stripper pins in so releasing the cotton from the take-off device. The holes in the shell 72 through which the stripper pins operate are sufficiently large that the air which enters the head through the opening 100 and 50 through the mouth passes through said holes, and serves as a cooling means to reduce the temperature of the shell due to the friction of the pins against the same. The air that passes through the shell serves also as 55 means to assist in releasing cotton from the take-off device at the rear of the same, this being auxiliary to the air flowing directly to the rear side of the device from the opening 100. Moreover air thus passing through 60 shell 72 clears the same of any foreign matter that may enter the same, such as sand and dirt enmeshed in the cotton fiber.

Much the larger percentage of the air by which the cotton is conveyed rearwardly 65 through the tube 14 enters the head through

the opening 100, although there is an appreciable flow of air through the mouth into the head. It will be understood that the cotton is passed intermittently through the head, due to the presentation of the head 70 from boll to boll, so that momentarily the air passes into the head and port and through the shell of the take-off device when the take-off device is free from cotton. At such and other times the air passes through the 75 shell 72 to cool and clean the same and to aid in stripping cotton from the pins 69.

What I claim as my invention is:

1. A cotton picking machine comprising a frame, a suction device carried thereby, a 80 picker head, a conveying tube connecting said picker head to said suction device, and a flexible transmission shaft connected to the picker head and extending backwardly to the frame, combined with means for counterbalancing the weight of the picker head, the conveying tube and said flexible shaft, said counterbalancing means being connected to the flexible shaft at a point intermediate its ends to prevent side whipping of 85 said shaft.

2. A cotton picking machine comprising a suction device, a picker head, a conveying tube connecting the picker head to said suction device, a jointed shaft connected to the 95 picker head and extending rearwardly therefrom, means to drive said shaft, and a counterweight connected to a section of said jointed shaft near said driving means and counterbalancing the picker head, shaft, and 100 tube.

3. A cotton picking machine comprising a suction device, a picker head, a conveying tube connecting the picker head to said suction device, a jointed shaft connected to the 105 picker head and extending rearwardly therefrom, means to drive said shaft, a counterweight connected to said jointed shaft near said driving means to counterbalance the picker head, shaft, and tube, and means for supporting the conveying tube, intermediate 110 the ends of the latter, from said shaft.

4. A cotton picking machine comprising a picker head and rotative, interacting picker brushes, combined with a take-off device in rear of and movable in contact with said brushes, embracing inner and outer rotative, eccentrically disposed elements, the latter perforated, and a series of stripper pins loosely connected to the inner 115 rotative element and movable into and out of the perforated element.

5. A cotton picking machine comprising a picker head and rotative interacting picker brushes, combined with a take-off 125 device in rear of and movable in contact with said brushes, embracing inner and outer rotative, eccentrically disposed elements, the latter perforated, a series of stripper pins loosely connected to the inner 130

rotative element and movable into and out of the perforated element and means to positively drive one rotative element from the other.

- 5 6. A cotton picking machine comprising a picker head and rotative interacting picker brushes, combined with a take-off device in rear of and movable in contact with said brushes, embracing inner and 70 outer rotative, eccentrically disposed elements, the latter perforated, a series of stripper pins loosely connected to the inner rotative element and movable into and out of the perforated element, with means to 75 drive the inner element, and a positive driving connection between the inner and outer rotative elements.
7. A cotton picking machine comprising a picker head embracing rotative, interacting 80 brushes, combined with a take-off device in rear of and movable in contact with said brushes, comprising a sleeve, with means to rotate it, a perforated shell eccentric to and surrounding said sleeve and provided with internal, annular bearings, supporting members having external, peripheral bearings overlapping and engaged by the internal bearings of said shell, and stripper pins connected to said sleeve and movable through the perforations of said shell. 85
8. A cotton picking machine comprising a picker head embracing rotative, interacting brushes, combined with a take-off device in rear of and movable in contact with 90 said brushes, comprising a sleeve, with means to rotate it, a perforated shell eccentric to and surrounding said sleeve and provided with internal, annular bearings, supporting members having external peripheral bearings overlapping and engaged by the internal bearings of said shell, stripper pins loosely connected at their inner ends to said sleeve and extending outwardly through the perforations of said shell, the 95 said perforations of the shell being enlarged inwardly to accommodate swinging movement of said pins relatively to their supporting sleeve, and means for positively driving the shell from said sleeve.
9. A cotton picking machine comprising a picker head embracing rotative, interacting brushes, combined with a take-off device in rear of and moving in contact with said brushes, comprising a shaft, a sleeve 100 mounted thereon, a series of picker fingers loosely connected at their inner ends to said sleeve and extending radially therefrom, a perforated shell eccentric to and surrounding said sleeve, through the perforations of which the stripper pins are movable, and a driving pin rigidly fixed to said shaft and sleeve and extending through an opening in said shell. 105
10. A cotton picking machine comprising a picker head formed to provide a mouth 110 and neck portion and a throat portion therebetween, and rotative, interacting picker brushes at said mouth, combined with a rotative take-off device at the throat and movable in contact with said brushes, comprising oppositely located blocks having external bearing surfaces, a shell having internal bearing surfaces supported on and rotative relatively to said blocks, a sleeve between said blocks axially eccentric to said shell, 115 and stripping pins carried by said sleeve and movable through the perforations of said shell.
11. A cotton picking machine comprising a picker head formed to provide a mouth 120 and neck portion and therebetween a throat portion, and rotative, interacting picker brushes at said mouth, combined with a take-off device at the throat and movable in contact with the brushes, comprising oppositely located blocks having external bearings, a shell having internal bearings supported on and rotative on said blocks, said blocks being provided with aligned, eccentrically disposed openings, a shaft extending through said openings, a sleeve supported on said shaft, stripper pins loosely carried by and rotative with said sleeve, and a pin fixed rigidly to said sleeve and shaft and extending outwardly into an opening in 125 said shell.
12. A cotton picking machine comprising a picker head formed to provide a mouth, a neck and a throat between the neck and mouth, and rotative, interacting picker 130 brushes at said mouth, combined with a rotative take-off device at said throat and movable in contact with said brushes, said take-off comprising oppositely located bearing members, a perforated shell overlapping at its ends supported on, and rotative relatively to, said bearing members, a rotative sleeve within and eccentric to said shell, and stripping pins carried by said sleeve and movable through the perforations of 135 said shell, said throat portion of the casing being enlarged at the sides of the take-off device.
13. A cotton picking machine comprising a picker head embracing a casing and a pair 140 of oppositely rotative, interacting brushes, movable take-off means in rear of and in contact with said brushes, and bearings for the shafts of said brushes, embracing overlapping portions on the casing and brush cores. 145
14. A cotton picking machine comprising a picker head embracing a casing, a pair of oppositely rotative, interacting brushes, and movable take-off means in rear of and in 150 contact with said brushes, and bearings for the shafts of said brushes embracing inwardly extending lugs on opposing casing walls, and shells extending endwise from the brush cores and overlapping said lugs. 155

15. A cotton picking machine comprising a picker head embracing a casing, a pair of oppositely rotative, interacting brushes, rotative take-off means in rear of and in contact with said brushes, and bearings for the shafts of said brushes embracing anti-friction elements and shells extending endwise from the brush cores and overlapping said bearings.
- 10 16. In a cotton picking machine, cotton picker means to directly engage the cotton bolls, a head inclosing the same having an open mouth and a take-off device in rear of and in contact with said picker means, embracing a perforated shell, through the perforations of which air passing into the head flows, and take-off fingers movable through the perforations of said shell, the perforations of the shell being enlarged inwardly, 15 thereby affording freedom of movement for the stripping pins.
17. A cotton picking machine comprising picker means adapted to engage and remove the cotton from the bur, and take-off means 20 acting against said picker means to remove the cotton therefrom comprising a perforated shell, fixed members having external bearings, said shell overlapping and rotating on said bearings, and a series of pins 25 extensible through the perforations of the shell and rotatable about an axis within the shell and eccentric to said external bearings.
18. A cotton picker comprising a picker head, picker means therein adapted to re- 30 move the cotton from the bur, and a take-off device to coact with the picker means comprising an outer rotative, perforated element, a second rotatable element inclosed within and eccentric to the outer perforated 35 element and grooved to receive the inner ends of take-off pins, take-off pins seated in the grooves of said inner element, and adapted to extend through the apertures of said shell, said pins being perforated at 40 their inner ends, and pivot pins extending 45
- through said second element and through the perforations of the take-off pins.
19. In a cotton picker, a picker head having a mouth, oppositely rotative, interacting brushes at said mouth having cores provided with extended shafts, bearings on opposite walls of the head in which said shafts are rotatively mounted, and shells extending endwise from the cores and overlapping said bearings.
20. A cotton picking machine comprising a picker head and rotative, inter-acting picker brushes, combined with a take-off device in rear of and movable in contact with said brushes, embracing inner and outer rotative, eccentrically disposed elements, the latter perforated, and a series of stripper pins loosely connected to the inner rotative element and movable into and out of the perforated element, the perforations of said outer element being enlarged inwardly to 60 accommodate movement of the pins due to the eccentricity of said inner and outer elements.
21. A cotton picking machine comprising a picker head embracing rotative, inter-acting brushes, combined with a take-off device in rear of and co-operating with said brushes, said take-off device comprising inner and outer rotative eccentrically disposed elements, the latter perforated, bearings in the head and overlapped by the ends of the outer element for supporting the latter, and a series of stripper pins connected to the inner rotative element and movable into and 65 out of the outer perforated element.
- In witness whereof I claim the foregoing as my invention, I hereunto append my signature in the presence of two witnesses at Atlanta, Fulton Co., Georgia, this eleventh 70 day of December, 1917.
